UNITED STATES PATENT OFFICE

2,512,061

ELECTRIC RADIATING HEATER

Alfred J. Huck, St. Louis, Mo., assignor to Knapp-Monarch Company, St. Louis, Mo., a corporation of Delaware

Application March 13, 1947, Serial No. 734,395

5 Claims. (Cl. 219—34)

1

My present invention relates to a heater which has a normally exposed heating element such as electric resistance wire wound on a core and located within a reflector and to a guard for the heating element, the invention being an improvement on my co-pending application Serial No. 567,947, filed December 13, 1944, now Patent 2,467,479, issued April 19, 1949.

One of the objects of the present invention is to provide a guard in the form of a shield in front of the heating element which prevents dresses, sashes or the like, which might get through the usual wire protective cage at the front of an electric type heater, from coming into contact with the resistance wire of the heater, the shield being protected from the heat of the heating element by a second shield interposed between the heating element and the first shield.

Another object is to provide a reflector or bowl type heater with means to positively roll it over on its back when it is accidentally tipped forwardly so that the reflector then points away from the rug or floor instead of permitting the concentrated heat from the heating element to be directed toward the floor.

A further object is to provide the foregoing improvements of such character that they do not interfere with the heat radiated from the heater, and can be much less expensively applied thereto than a fine screen outside the guard wires which, though a solution, does not produce a good appearing and saleable article.

With these and other objects in view, my invention consists in the construction, arrangement and combination of the various parts of my device whereby the objects contemplated are attained as hereinafter more fully set forth, pointed out in my claims, and illustrated in the accompanying drawings, in which:

Fig. 1 is a perspective view of a reflector type heater with my safety guard arrangement applied thereto;

Fig. 2 is a sectional view through the center of the heater showing the heating element guard or shield in place and a second or intermediate shield between it and the heating element;

Fig. 3 is a front elevation of the intermediate shield looking in a righthand direction at it in Fig. 2;

Fig. 4 is a view from the top showing the

2

heater tipped forwardly and contacting a floor surface to illustrate an unstable position from which the heater will roll over on its back to avoid directing heat rays toward such surface.

5 Fig. 5 is a diagrammatic view showing different forms of support for the shields, the shields being supported from the reflector of the heater.

10 Fig. 6 is a similar diagrammatic view of another modified form of support in which the shields are supported from a wire cage guard of the heater, and

Fig. 7 is a diagrammatic view showing relative radii and diameters that I have found most suitable for a guard of the character disclosed.

15 15 On the accompanying drawing I have used the reference numeral 10 to indicate a base and 12 a reflector of a reflector type heater. The reflector 12 has the usual guard formed of wires 14 and a connecting disk 17 at the center. Within the reflector 12 a heating element HE is provided. The heating element HE may be in the form of a ceramic core 16 on which is wound a resistance wire 18, the heating element being supported by a pair of bolts 20 which also serve as terminal connectors for the resistance wire. These terminals may be connected with an electric service cord 22 extending into a housing 24 within which the electrical connections are made.

20 30 As shown in my co-pending application, a guard 26 is provided in the form of a shield which may or may not be cupped as disclosed and which may be supported on the heating element HE by means of a screw 28 threaded into a cross bar 30. The cross bar 30 has its ends received in opposite openings 32 of the core 16.

35 40 I found that when the shield 26 was supported directly against the outer or left end of the core 16 in Fig. 2 the intense heat from the heating element discolored it. The shield is preferably plated with chromium or the like for the sake of appearance and such discoloration is therefore objectionable. I have accordingly provided an intermediate shield 34 interposed between the core 16 and the shield 26 and spaced from both

45 50 of them as by inturned ears 36 and outturned ears 38. The shield 34 may also be cupped as illustrated. Three of the ears 36 and three of the ears 38 may be provided as illustrated in Fig. 3.

50 The intermediate shield 34 may become quite

hot without the outer shield 26 being discolored and the shield 34 thereby shields the shield 26 from the direct rays of heat from the resistance wire 18 and also from reflected rays of heat. There is also some thermal circulation of air upwardly between the shields 34 and 26 to carry away excessive heat and thus prevent discoloration. This also prevents the shield 26 from attaining as high a temperature as it otherwise would, as the shield 34 cuts down heat transfer to the shield 26. The guard characteristics of the shield 26 are thereby enhanced.

The wire guard 14 has one wire indicated at 15 which it will be noted is bulged farther away from the reflector 12 than the others. This is the lowermost center wire of the guard and has this different shape for a specific reason, as will hereinafter appear.

The base 10 has a pointed projection indicated at 40 and located at the front end of the base. The wire 15 and the projection 40 cooperate with each other as shown in Fig. 4 to provide a two point support for the heater if it is accidentally tipped forward onto the floor surface indicated at 42. If the heater is sidewise from the position shown in Fig. 4 when it strikes the floor, then it will automatically roll over on its back due to the curvature of the guard wires 14 and the curvature and weight distribution of the base 10, and the curvature of the reflector 12. To prevent it from staying in the position of Fig. 4 however the wire 15 and the projection 40 serve as pivots so that the heater is in an unstable position if it tips straight forward and must then of necessity tip out of that position so that it will roll over on its back. This prevents the radiated and reflected heat rays from the heater being directed toward the surface 42, but instead they will be directed upwardly and there is no danger then that the floor will be burned by the heater.

As shown in my co-pending application, the shield 26 need not necessarily be a cupped sheet metal guard as it may take other shapes and be formed of other materials. The intermediate shield 34 may also be formed of suitable materials other than metal, if desired, and both shields may be supported in any suitable manner rather than on the heating element itself. The disclosed arrangement provides an efficient portable radiant heater from which the majority of the radiated heat is emitted outside the shield. Tip-over objections are met with a smaller size device for the wattage used. This is an obvious economy of manufacture.

While I have shown in Fig. 2 a means of supporting the shields 26 and 34 from the heating element HE, they can be supported by other methods such as shown in Figs. 5 and 6. In Fig. 5 a plurality of struts 28a may extend from the reflector, past the shield 34 to the shield 26 and be suitably secured to both shields as by spot welding or the like. The struts 28 may be formed of sheet metal and in any desired number, preferably three, the outer ends being spot welded or otherwise suitably secured to the reflector.

In Fig. 6 I show a strut 28c in the form of a post (preferably tubular) extending from a central disc 17 that serves as a name plate on the wire cage 14 to the shield 26 for supporting it. A second strut 28d forms an extension of the strut 28c for supporting the shield 34 from the shield 26. Thus it is obvious that the shields 26 and 34 need not necessarily be supported by the heating

element itself in order to serve as a guard against articles contacting the heating element.

I have found that certain constants produce maximum efficiency in a guard of the kind herein disclosed. Referring to Figure 7, several dimensions are shown and these I find are more or less critical and bear approximately the following relations to each other:

$$\begin{aligned} D &= 1.56R \\ D^1 &= .643R \\ D^2 &= .238R \\ R^1 &= .353R \end{aligned}$$

15 These seem to be the critical dimensions although other dimensions such as the spacing of the heating element HE from the reflector 12 and the guards 26 and 34 from the heating element are somewhat critical and approximately of the proportions illustrated in Figure 7.

The arrangement including the intermediate shield 34 provides a practical construction wherein the intermediate shield prevents discoloration to the outer shield 26 which is preferably chrome plated for appearance sake. The shape of the inner shield 34 is a compromise between that of the outer shield and the forward end of the heating element HE. The arrangement makes possible a relatively small heater and a safety shield applied thereto with the heating element rated at 600 watts or more. I find that not much variation from the above listed proportions can be tolerated for a practical design.

Some changes may be made in the construction and arrangement of the parts of my device without departing from the real spirit and purpose of my invention, and it is my intention to cover by my claims such modified forms of structure or use of mechanical equivalents as may be reasonably included within their scope.

I claim as my invention:

1. In an electric heater structure, a heater, a reflector therefor, a safety guard comprising a shield element adjacent and spaced from the outer end of the heater in a position opposite said reflector to prevent inflammable articles entering said reflector from engaging said heater, and a second shield element interposed between said first shield element and said heater and thereby also opposite said reflector, said second shield being spaced from both said first shield element and said heater to reduce the heat radiated and reflected to the first shield element.

2. In an electric heater device, a heater, a reflector therefor, a safety guard comprising a cupped guard shield to guard articles entering the reflector from contact with said heater, said guard shield being supported in spaced relation to the forward end of said heater, and an intermediate cupped shield to reduce heat transmission to the first guard shield, said intermediate shield being formed of sheet metal and having fingers extending rearwardly to engage said heater and other fingers extending forwardly to engage said first guard shield and space both shields and the heater in relation to each other.

3. A heater structure having a heater and a reflector therefor, and a safety guard for said heater comprising a cupped shield in front of said heater and extending back over its outer end, and an intermediate partition to reduce heat transmission to said shield, said partition being cupped and also extending back over the outer end of said heater and being spaced from both 75 the heater and the shield to permit thermal cir-

culation in both spaces said partition terminating within said shield.

4. In an electric heater structure, a heater, a reflector therefor, a cupped shield to guard articles entering the reflector from contact with said heater, said shield being supported in spaced relation to the forward end of said heater, and an intermediate shield to reduce heat transmission to the first shield, the dimensions of said heater, said reflector and said first shield being substantially as follows in relation to the radius (R) of curvature of the reflector:

Diameter of reflector _____ 1.5R
 Diameter of shield _____ .65R
 Diameter of heating element _____ .24R 10
 Radius of curvature of shield _____ .35R

5. In an electric heater structure, having a heater, a reflector therefor, a cupped guard shield to guard articles entering the reflector from contact with said heater, said guard shield being supported in spaced relation to the forward end of said heater, and an intermediate cupped

shield to reduce heat transmission to the first guard shield, the diameter of said reflector being substantially $1.5R$, the diameter of said guard shield being substantially $.65R$, the diameter of said heater being substantially $.24R$ and the radius of curvature of said guard shield being substantially $.35R$ wherein R is the radius of curvature of said reflector.
